The ornamental design for an illuminating device, as shown and described.

DESCRIPTION

FIG. 1 is a side view of an illuminating device showing our new design;

FIG. 2 is a front view thereof;

FIG. 3 is a rear view thereof;

FIG. 4 is a top view thereof;

FIG. 5 is a bottom view thereof;

FIG. 6 is a front perspective view thereof; and,

FIG. 7 is a rear perspective view thereof.

The broken lines immediately adjacent to the shaded regions form unclaimed boundaries of the design. The broken line showing of the remainder of the illuminating device is for illustrative purposes only and forms no part of the claimed design.
